UNITED STATES PATENT OFFICE.

CHARLES J. STROSACKER AND CLARENCE C. SCHWEGLER, OF MIDLAND, MICHIGAN,
ASSIGNORS TO THE DOW CHEMICAL COMPANY, OF MIDLAND, MICHIGAN, A COR-
PORATION OF MICHIGAN.

METHOD OF PURIFYING ACETIC ANHYDRIDE.

No Drawing.

Application filed November 13, 1918. Serial No. 262,336.

To all whom it may concern:

Be it known that we, CHARLES J. STROSACKER and CLARENCE C. SCHWEGLER, citizens of the United States, and residents of Midland, county of Midland, State of Michigan, have jointly invented a new and useful Improvement in Methods of Purifying Acetic Anhydride, of which the following is a specification, the principle of the invention being herein explained and the best mode in which we have contemplated applying that principle, so as to distinguish it from other inventions.

Acetic anhydride ($\text{CH}_3\text{CO}_2\text{O}$), as is well known, is a reagent of great importance in the manufacture of organic compounds particularly for converting primary and secondary amines into acetyl derivatives. As an incident of its manufacture, the commercial article, however, is almost always found to contain some sulphur, this sulphur being mainly in the form of thio anhydride, $(\text{CH}_3\text{CO})_2\text{S}$, which impurity is objectionable in connection with the use of acetic anhydride, and at the same time extremely difficult to eliminate, since its boiling point and that of such anhydride are substantially identical. The object of the present invention is to provide a simple and convenient process for the purification of acetic anhydride by the elimination of the sulphur compounds in question. To this end the invention consists of the steps hereinafter fully described and particularly pointed out in the claims, the following description setting forth in detail an approved mode of carrying out the invention, such disclosed mode, however, constituting but one of the various ways in which the principle of the invention may be used.

In carrying out our improved process we treat the crude acetic anhydride with a chloride or bromate, or with a metallic oxide,

preferably manganese oxide. Since such crude acetic anhydride requires to be redistilled in order to eliminate other impurities, we find it convenient to introduce the reagent, thus designed to eliminate the sulphur, at this stage, mixing it with the anhydride as it is introduced into the still. All of the reagents named are insoluble in the anhydride but readily unite with any sulphur compounds that may be present. The amount of the reagent added will be gauged to correspond with the amount of the sulphur as previously determined.

Other modes of applying the principle of our invention may be employed instead of the one explained, change being made as regards the method herein disclosed, provided the step or steps stated by any of the following claims or the equivalent of such stated step or steps be employed.

We therefore particularly point out and distinctly claim as our invention:

1. In a method of purifying acetic anhydride containing a sulphur compound of approximately the same boiling point as an impurity, the steps which consist in introducing into such anhydride a metallic oxide insoluble therein but capable of readily uniting with such sulphur compound, and then distilling.

2. In a method of purifying acetic anhydride containing a sulphur compound of approximately the same boiling point as an impurity, the steps which consist in introducing into such anhydride an oxide of manganese insoluble therein but capable of readily uniting with such sulphur compound, and then distilling.

Signed by us, this 8th day of November, 1918.

CHARLES J. STROSACKER.
CLARENCE C. SCHWEGLER.
